(57) **CLAIM**

We claim the ornamental design for a receptacle, as shown and described.

DESCRIPTION

FIG. 1 is a top perspective view of a receptacle showing our new design;

FIG. 2 is a bottom perspective of the receptacle of FIG. 1; FIG. 3 is a top view of the receptacle of FIG. 1; and, FIG. 4 is a bottom view of the receptacle of FIG. 1.

The broken lines in the drawings depict portions of the receptacle that form no part of the claimed design.

1 Claim, 3 Drawing Sheets(56)
